UNITED STATES PATENT OFFICE.

FRANCIS A. MILLS AND JAMES MUNDELL, OF PHILADELPHIA,
PENNSYLVANIA.

LAST.

SPECIFICATION forming part of Letters Patent No. 588,718, dated August 24, 1897.

Application filed April 13, 1896. Renewed July 24, 1897. Serial No. 645,852. (No model.)

To all whom it may concern:

Be it known that we, FRANCIS A. MILLS and JAMES MUNDELL, citizens of the United States, residing at Philadelphia, in the county of 5 Philadelphia and State of Pennsylvania, have invented new and useful Improvements in Lasts for Boots or Shoes, of which the following is a specification.

Our improvement consists in providing the 10 wooden last with a metal heel-pin by which it is held and manipulated on the jack or nailing-machine, whereby the shoe may be completed on one and the same last.

As now practiced in the trade the wooden 15 last is used in the manufacture of boots and shoes and is formed with the heel-socket, for the jack-post. In this work the shoe is lasted on the wooden last, and this last is then withdrawn from the shoe with much trouble and 20 an iron last is inserted in the shoe with much trouble for the purpose of heeling the shoe in the nailing-machine. This changing of lasts not only involves a loss of time, but disfigures the shoe and increases the cost of 25 production.

Our improvement gives greater strength to the wooden last and permits the shoe to be both lasted and heeled thereon in much less time and trouble than with lasts having heel-30 sockets adapted to be supported upon the jack-post. In providing the wooden last with the metal holding and guiding pin which relieves the last of the nailing blows it gives the advantage that every last has its own guide-35 support, which gives the same distance from the bottom of the heel of the last to the end of the guide-pin, so that when the lasting or heeling machine is once set it is ready and set for every last.

40 The accompanying drawings show, in Figure 1, our improved last partly in vertical section. Fig. 2 is a side view of the same; and Fig. 3 is a vertical section showing the manner of securing the guide-pin and the heel-45 plate and locking them together and to the last, so that neither the heel-plate nor the guide-pin can work loose.

The last has the usual iron plate *a*, which 50 covers the surface of the heel and against which the nails are driven into the heel of the shoe. Centrally piercing this heel-plate is a

screw-threaded hole *b*, and the last is pierced with a hole *c* coincident with the hole in the heel-plate. The guide-pin *d* for the last is driven tightly into the hole in the last and is 55 screwed into the heel-plate and extends above the cone of the last a sufficient distance to form the support and guide for the last in the lasting or nailing machine, which, it will be understood, is provided with a suitable socket 60 to receive the last-pin. To prevent the screw guide-pin from turning and becoming loose in the last, it is locked by a pin *g*, driven through a hole in the last and through a hole in the guide-pin and clenched upon washers 65 at the sides of the last, as seen in Fig. 1.

The last is recessed to receive the heel-plate, and in driving the guide-pin into the screw-threaded hole of said plate the latter would be liable to be turned out of true position with 70 the heel and to break the shoulder of the heel-recess. To prevent the turning of the heel-plate, it may be either fastened by screws or it may be provided with spurs *h* on its inner side, which pierce the last and hold the plate 75 against the force of screwing the guide-pin into it; but when the heel-plate is seated and the last-pin screwed into it and locked by the clenching-pin the heel-plate will be firmly 80 secured in the last. This construction produces a solid wooden last, and it produces a last which has its own guide-pin for the nailing-machine, and on this wooden last the shoe 85 is both lasted and heeled, and this is the important feature of our improvement.

The improvement is important because it adapts the wooden last for use with the automatic nailing-machine, where the exact measurement for the nail to be cut is maintained 90 for every last, because the distance from the nailing-surface of the heel-plate to the end of the guide-pin is the same in every last and fits the adjustment of the nailing-machine when once made. The improvement avoids 95 the necessity for using adjustable heel-posts in the nailing-machine, it avoids the use of metal bushings or of metal socket-blocks piercing the heel, and it avoids the use of heavy iron lasts formed with projecting heel-stems which have been proposed for use with 100 a socket-holding part on the nailing-machine,

and it provides a cheap and light last for all the work of making the shoe and for use with any lasting or nailing machine or jack.

When the last is provided with the usual 5 yoke *f* for strengthening the heel which sustains the force of the blows in nailing on the heel of the shoe, the pin *g*, which locks the last guide-pin from turning, serves also as the means of securing the strap over the cone of 10 the last, as seen in Figs. 2 and 3. The guide-pin for the last may also be provided with a shoulder *e*, which, when the guide-pin is driven home in the screw-socket of the heel-plate, will abut upon the cone of the last or upon 15 the strap and thereby cause the heel-plate to be drawn upon its seat and clamped and held firmly in place when the guide-pin is locked. This construction produces a cheap, strong, and durable wooden last for the work 20 of lasting and heelng the shoe, for it will be seen that the force of the blows of the nailing-machine will be borne entirely by the iron heel guide-pin.

The screw-socket of the heel-plate is formed 25 in a boss to give a proper hold for the guide-pin.

It is not deemed necessary to show the post or arm of the nailing-machine, but it will be understood that it is provided with a socket 30 adapted to receive the guide-pin of the last and that it has a pin adapted to enter a hole *i* in the last for the purpose of holding the last rigid with the machine and causing the last and the machine to turn together as the 35 position of the machine is changed or shifted laterally for right and left heelng.

The screw connection of the last guide-pin and heel-plate is preferred, but the guide-pin and heel-plate may be riveted together or 40 otherwise secured, so that they will be as a single piece when secured in the last, and two or more clench-pins may pass through the last and its guide-post, so that as an article of manufacture our wooden last takes the 45 place of the two lasts now used in the trade for lasting and heelng shoes.

We claim—

1. The combination, with a wooden last having a metallic heel face-plate, pierced with 50 a screw-threaded hole, of a guide-pin having a screw-thread for engaging said heel-plate and passing through the heel terminates above its cone, for the purpose stated.

2. The combination, with a wooden last

having a metallic heel face-plate pierced with 55 a screw-threaded hole and a yoke-strap embracing the cone of the last, of a guide-pin having a screw-thread for engaging said heel-plate and passing through the heel and its yoke-strap terminates above its cone, provided with a shoulder for engaging said yoke-strap, whereby to clamp and firmly secure the heel-plate. 60

3. The combination, with a wooden last having a metallic heel face-plate pierced with 65 a screw-threaded hole, of a guide-pin having a screw-thread for engaging said heel-plate and passing through the heel terminates above its cone and having a shoulder adapted to engage the cone of the last, and a clench-pin 70 passing through the last and its guide-pin substantially as described.

4. The combination, with a wooden last having metallic heel face-plate pierced with a screw-threaded hole, of a guide-pin having 75 a screw-thread for engaging said heel-plate and passing through the heel terminates above its cone and means for locking said guide-pin and last together, for the purpose stated.

5. The combination with a wooden last 80 having a metallic heel face-plate and a yoke embracing the cone of the heel, of a guide-pin for the last passing through the yoke-strap at the cone of the heel and having a shoulder for engaging said yoke-strap and having also 85 a screw for engaging a threaded hole in said heel-plate, and a pin passing through the yoke-strap and through the guide-pin for the purpose stated.

6. The combination, with a wooden last 90 having a metallic heel face-plate pierced with a screw-threaded hole and having spurs on its inner face for engaging the last, of a guide-pin for the last having screw-threads for engaging said heel-plate, and a pin passing 95 through the said guide-pin for the purpose stated.

7. The combination, with wooden last having a metallic heel face-plate, a metallic guide-pin rigidly secured to said heel-plate, passing 100 through the heel and a riveted pin locking said guide-pin to the last.
